UNITED STATES PATENT OFFICE.

FREDERICK C. BRADBURN, OF ROCHESTER, NEW YORK, ASSIGNOR TO DAYLIGHT PHOTO SPECIALTY COMPANY, OF ROCHESTER, NEW YORK.

PHOTOGRAPHIC APPARATUS.

No. 901,308.

Specification of Letters Patent.

Patented Oct. 13, 1908.

Application filed February 23, 1907. Serial No. 358,863.

To all whom it may concern:

Be it known that I, FREDERICK C. BRADBURN, of Rochester, in the county of Monroe and State of New York, have invented certain new and useful Improvements in Photographic Apparatus; and I do hereby declare the following to be a full, clear, and exact description of the invention, such as will enable others skilled in the art to which it appertains to make and use the same.

My invention relates to photographic apparatus and more particularly to an improved day-light developing tray, the object of the invention being to simplify and improve the developing device for which Letters-Patent were granted to me on the 4th. day of December 1906 and designated by No. 837,541.

With this object in view, the invention consists in certain novel features of construction and combinations and arrangements of parts as hereinafter set forth and pointed out in the claims.

In the accompanying drawings, Figures 1 and 2 are perspective views of the device; Fig. 3 is a longitudinal sectional view; Fig. 4 is a transverse sectional view with a plate holder in position on the developer.

1 represents the developing tray, which 30 may be conveniently made of sheet metal and provided with a bottom 2 which consists of a sheet of transparent glass or other suitable material, colored to prevent the passage of actinic light rays. The sides 3, 3, and 35 ends 4, 5 of the tray may be composed of a single sheet of metal bent into rectangular form, or the front end 4 may be made separate and soldered to the sides. The metal of the sides and ends of the tray are bent inwardly at their lower edges and provided at the inner edges with beads 6 on which the colored glass bottom 2 of the tray rests. The beads 6 form gutters to receive cement, by means of which the glass bottom is secured in place. Against the inner faces of the sides, metal strips 7, 7, are disposed, and these strips are provided at their lower edges with flanges 8 which project over the side edges of the glass bottom 2 and are cemented 45 to the latter. Similar strips 9, 10 are disposed against the inner faces of the end walls of the tray and provided at their lower edges with flanges 8 which overlap the ends

of the glass bottom 2. The side strips 7 and front end strip 9 are provided at their upper edges with inwardly projecting flanges, which constitute ledges 11 for the reception of a removable transfer frame 12 having a colored transparent slide 13 which constitutes the top of the developing chamber 14 of the tray. Thus it will be seen that the chamber 14 is confined to the space below the ledges 11 and the transfer device which rests thereon, and that said chamber is made with double walls.

The sides 3, 3, of the tray project some distance above the ledges 11, and constitute, in effect, flanges which receive the transfer frame between and which also receive between them and serve as light seals for a plate holder as hereinafter more fully described. The front end 4 of the tray projects only a short distance above the adjacent ledge 11 to form a short flange 15, against which the front end of the transfer frame 12 abuts to form a light seal. The rear end wall of the tray extends upwardly the same distance as the side walls, as does also the end strip 10 against the inner face of said end wall. The double end wall thus formed, co-operates with portions of the sides 3 of the tray, to form a fluid chamber 16, the bottom of which is a continuation of the bottom of the developing chamber 14 and said chambers 14 and 16 are in free communication with each other, with no ledges or shoulders between them. Therefore no splashing of developing fluid will occur when the latter is made to flow over a negative in the process of developing the same. The fluid chamber 16 is provided with a permanent sheet metal cover 17 having a depending flange 18 at its inner edge. The flange 18 terminates at its lower edge in a plane coincident with the plane of the ledges 11 and is itself provided with a ledge 11. The top or cover 17 of the fluid chamber is provided with an opening with which a tube 20 located in said chamber, may be made to communicate, for introducing the developing fluid. This inlet 100 may be normally closed by means of a suitable cap 21. The side ledges 11 may be strengthened by means of posts 22, the lower ends of which are provided with inwardly projecting toes 23 resting upon the flanges 8. Upon these toes, the negative will be sup-

ported slightly above the glass bottom 2 during the process of development. A post 24 is also located between the bottom 2 and the lower edge of the front wall or flange 18 of the fluid chamber to prevent the negative from entering the latter. The wall or flange 18 is made with a slight depression 25 just over the adjacent ledge 11 and in this depression, a spring 26 is secured and adapted to press against one end of the transfer frame 12 so as to press the other or front end of the latter, snugly against the flange 15 at the front end of the tray and thus insure a light seal at this point.

The transfer frame 12 hereinbefore referred to, may be made of wood or other suitable material and the slide 13 may be a thin sheet of transparent, colored celluloid. For the accommodation of the slide, one end of the transfer frame is provided with a slot, and the other end of the frame and the sides thereof are made with grooves.

The device constructed as herein described, is intended to receive a previously exposed photographic plate from a plate holder, and permit the developing of the plate in the daylight, and without any necessity whatever for resort to a dark room, either for transferring a plate from a plate holder to the bath or in developing said plate.

In Fig. 4 of the drawing, I have shown a plate holder in the position which it will occupy when a previously exposed plate is to be placed into the developing chamber. The plate holder 27 is placed upon the transfer frame 12 within the chamber formed by the flanges of the sides 3 and end wall 18 so as to be closely embraced by said flanges and end wall, and said plate holder is provided in its under face near its front end with a rib to enter a groove 29 in the front portion of the transfer frame 12 to form a light seal at this point.

In the drawing, I have shown a holder 27 adapted for the reception of a single plate, but it is evident that the ordinary double plate holder might be used. When the ordinary plate holder is used, the plate may be released from the holding spring commonly employed, by means of a lip 30 on the rear end of the transfer frame 12.

With the plate holder 27 in the position shown in Fig. 4 and the plate released from its holding means and resting upon the holder 55 shutter 31, said shutter will be withdrawn for the purpose of permitting the plate to drop upon the slide 13 in the transfer frame. The shutter 31 may now be replaced, and the slide 13 withdrawn to permit the plate to drop into the developing chamber. The plate having been thus deposited into the developing chamber, the slide will be replaced and the plate holder removed. The operator may now proceed to develop the negative, holding the device up to the light and looking

through it from time to time to observe the process of development. When the negative shall have been properly developed, the operator will remove the transfer frame and then he will have access to the plate for the purpose of removing it to a fixing bath. Before removing the plate from the developing tray, the operator may dispose the latter vertically to permit the developing solution to drain from the plate and enter the fluid chamber 16.

When a plate holder is used, having ribs on its bottom near its sides and one end, and a groove near its other end,—one face of the transfer frame 12 is provided with grooves 32 parallel with its sides and one end to receive the ribs on the plate holder, and a rib 33 is provided near the other end of the transfer frame to enter a groove in the plate holder, for the purpose of forming light seals between such holder and the transfer frame.

Various slight changes might be made in the details of construction of my improved developing device, without departing from the spirit thereof as defined by the claims.

Having fully described my invention what I claim as new and desire to secure by Letters-Patent, is:—

1. A day-light developer, comprising a tray having a transparent non-actinic bottom, and a removable transfer device embraced by the side walls of the tray and comprising a transparent non-actinic slide constituting the top of the developing chamber, and a removable holder for said slide, said slide and its holder disposed below the upper edges of the side walls of the tray.

2. A day-light developer comprising a tray having a transparent, non-actinic bottom, ledges within said tray at the top of the developing chamber and below the upper edges of the walls of the tray, a removable frame mounted on said ledges and disposed below the upper edges of the side walls of the tray, and a transparent non-actinic slide mounted in and carried by said removable frame and constituting the top of the developing chamber.

3. A day-light developer comprising a tray having a developing chamber, and a fluid chamber communicating therewith, and having walls projecting above the top of the developing chamber, a removable frame disposed within the space bounded by said walls, and a transparent slide of non-actinic material carried by said frame and removable therewith.

4. A day-light developer comprising a tray provided with a transparent non-actinic bottom, said tray having a developing chamber and a fluid chamber in free communication with the developing chamber, a ledge around the top of the developing chamber, posts under the side members of said ledge and lugs or toes at the lower ends of the posts for support-

- ing a plate above the bottom of the tray, and a slide of transparent non-actinic material supported by said ledge.
5. A day-light developer, comprising a tray provided with a transparent non-actinic bottom and having a developing chamber, a transfer frame, a transparent non-actinic slide carried by said frame, and a lip projecting upwardly from one end of said frame.
10. 6. A day light developer, comprising a tray having a developing chamber and a fluid chamber having free and unobstructed communication with the developing chamber, said tray having a plate extending from end to end thereof and constituting a continuous bottom for both of said chambers, a frame supported within the tray over the developing chamber and a transparent non-actinic slide carried by said frame and constituting the cover of the developing chamber.
15. 7. A day light developer, comprising a tray provided with a transparent non-actinic bottom, strips disposed against inner walls of said tray and provided at their upper edges with flanges which constitute ledges, and a transfer frame resting on said ledges and provided with a transparent non-actinic slide constituting the top of the developing chamber.
20. 8. A day-light developer comprising a tray having a non-actinic bottom and provided with ledges above said bottom, a flange at the front end of the tray projecting above the ledge at said front end, a removable frame resting on said flanges, a spring to press the front end of the removable frame against the flange at the front end of the tray, and a transparent non-actinic slide in said removable frame constituting the top of the developing chamber.
25. 9. A day-light developer comprising a tray provided with a transparent non-actinic bottom and a developing chamber over said bottom, said developing chamber having double walls, ledges at the top of the developing chamber and below the top of the side
- walls of the tray, a frame resting on said ledges, and a transparent non-actinic slide in said frame.
30. 10. A day-light developer comprising a tray having sides and ends provided at their lower edges with inwardly projecting flanges, a transparent non-actinic bottom resting upon said flanges and cemented thereto, ledges within said tray, and a transparent, 55 non-actinic slide supported by said ledges and constituting the top of a developing chamber.
35. 11. A day light developer comprising a tray having sides and ends provided at their lower edges with inwardly projecting flanges, a transparent, non actinic bottom resting on said flanges and cemented thereto, strips disposed against the inner faces of said sides and ends and provided at their lower edges 60 with inwardly projecting flanges overlapping the edges of the transparent, non-actinic bottom, and a transparent, non-actinic slide disposed within the tray and constituting the top of a developing chamber. 70
40. 12. A day-light developer comprising a tray provided with inwardly projecting flanges at the lower edges of its sides and ends, a transparent, non-actinic bottom resting upon said flanges and cemented thereto, 75 strips disposed against the inner side faces of the sides and ends of the tray and provided at their lower edges with inwardly projecting flanges overlapping the edges of the transparent non-actinic bottom, the strips at the 80 sides and one end of the tray having inwardly projecting flanges at their upper edges, and a transparent, non-actinic slide supported by said last-mentioned flanges and constituting the top of a developing chamber. 85
